UNITED STATES PATENT OFFICE

135,681

DESIGN FOR A GAME BOARD

William G. Fletcher, Bogota, N. J.

Application November 26, 1942, Serial No. 108,881

Term of patent 14 years

To all whom it may concern:

Be it known that I, William G. Fletcher, a citizen of the United States, residing at Bogota, in the county of Bergen and State of New Jersey, have invented a new, original, and ornamental Design for a Game Board, of which the following is a specification, reference being had to the accompanying drawing, forming part thereof, wherein—

I claim:
The ornamental design for a game board, substantially as shown.

WILLIAM G. FLETCHER.
